UNITED STATES PATENT OFFICE.

HARRY CLARK, OF CHICAGO, ILLINOIS.

DESIGN FOR A FLOWER BOX.

Application filed October 26, 1927. Serial No. 23,895. Term of patent 3½ years.

To all whom it may concern:

Be it known that I, HARRY CLARK, a citizen of the United States, residing at Chicago, in the county of Cook and State of Illinois, have invented a new, original, and ornamental Design for a Flower Box, of which the following is a specification, reference being had to the accompanying drawing, forming a part thereof.

Fig. 1 is a side view; and

Fig. 2 is an end view of a flower box showing my new design.

I claim:

The ornamental design for a flower box, as shown.

HARRY CLARK.
